Filed June 6, 1961, Ser. No. 65,489

Term of patent 14 years

(Cl. D71—1)

FIG. 1.

FIG. 2.

FIG. 3.

FIG. 4.

FIG. 1 is a top plan view of an airship showing my new design.

FIG. 2 is a side elevation thereof. The opposite side of the airship from that shown is the same in appearance as the side shown.

FIG. 3 is a front elevation of the airship.

FIG. 4 is a rear elevation of the airship.

The instantly disclosed airship is characterized by the particular area located behind the center element and between the two side elements.

I claim:

The ornamental design for an airship, as shown and described.
